VERIFYING MACHINE FOR PERFORATED CARDS

Knut Andreas Knutsen, Paris, France

Application October 20, 1938, Serial No. 236,039
In France October 29, 1937

11 Claims. (Cl. 73—51)

The present invention relates to verifying machines for perforated cards or bands. Said machines comprise a carriage for the step by step advance of the card, and an escapement mechanism controlled by a hand operated keyboard. When a perforated column of the card is in position to be verified, the operator depresses one or a plurality of keys, corresponding to one or a plurality of indications from the document from which the card has previously been perforated. If the key or keys which have been depressed correspond to the perforations of the column of the card in position to be verified, the escapement will be actuated, the card skips one column, and the verification of the next column may take place. If, on the contrary, said keys did not correspond to said perforations, the machine is locked.

An object of the present invention is an improved construction which increases the security and the speed of said machines. According to the invention, the electric operation of the machine necessitates only a reduced and small number of magnets.

A further object of the invention consists in a marking device which automatically provides every column being verified with the imprint "verified." Another mark "error" different from the first one is applied on the columns verified incorrect.

According to a feature of the invention, said first imprint may be omitted on the empty columns of the card. If the machine is blocked according to the verification of a column which is supposed to have no perforation, the imprint "error" is marked on said column.

Another object of the invention is a verifying machine which will register any wrong operation of the keys by the operator. According to the invention, if the operator operates the keyboard in a way that does not correspond to the perforations of the column which is just being verified, the machine is blocked and it is necessary in order to continue the verification or to eject the card that the error key should be depressed whereby the error will be automatically registered.

In the existing machines, when the operator depressed a wrong key, the machine was blocked, but said machines permitted the operator to try afterwards the other different keys of the keyboard. Thus when the operator depressed the right one or ones of said keys, the machine was unblocked, the operator could continue the veri-

fication, and no trace of said inaccurate operation was left on the card.

For instance, assume that a card contains in the column which is just to be verified, a perforation 2, which is incorrect, and that the operator depresses the key 3 which corresponds to a correct perforation of said column; consequently the machine will be blocked. In the existing machines the operator may then depress the key 2, which will unlock the machine, and the operator may continue the verification of the next column. No mark on the card will indicate that the card contains an incorrect perforation.

According to the present invention, the machine is blocked as a result of discord between the operation of the keyboard, and the perforation or perforations in the column to be verified, and the machine can only be unlocked by the operation of a key "error." The operation of said key "error" will apply an imprint "incorrect" on the column just being verified, indicating that the perforation or perforations of the column did not correspond to the original document, or that the operator has depressed a wrong key.

According to another feature of the invention, if the machine has been blocked during the verification of a card, said card will be ejected separately.

The invention comprises finally a mechanism for automatically verifying empty fields on the cards.

A preferred embodiment of the invention will now be described by way of example only, with reference to the accompanying drawings, in which:

Fig. 1 is a side view and partly a section of the machine.

Fig. 2 is a plan view of the mechanism shown in Fig. 1.

Fig. 3 shows in position of rest a part of the ejecting mechanism for the incorrect cards.

Fig. 4 shows in operating position the same mechanism as Fig. 3.

Fig. 5 is a longitudinal section of the reading device.

Fig. 6 is a side view of the mechanism shown in Fig. 4.

Figs. 7, 8 and 9 show the locking mechanism.

Fig. 10 is a wiring diagram.

Fig. 11 is a section of the printing device.

Fig. 12 is a view of the key "error."

Fig. 13 is a side view of the mechanism shown in Fig. 12.

Fig. 14 is a plan view showing the inking ribbon.

Figs. 15, 16 and 17 show details of the mechanism shown Fig. 7.

Fig. 18 is another form of execution of the wiring diagram.

Figs. 19 and 20 show cards provided with the imprints "verified" and "error."

Figs. 21, 22 and 23 show details of the escapement mechanism.

Fig. 24 shows details of the ejecting mechanism.

Feeding and ejecting mechanism

The cards to be verified are introduced in a receptacle 101 Fig. 1. The operator depresses the key 294 Fig. 10 which closes the contact 124 and establishes the circuit for the motor as explained later. The motor 102 Fig. 1 is fixed on the frame 103. On the motor shaft is fixed a toothed wheel 104 which by the intermediate wheel 105 is geared to the wheel 106 fixed on a spindle 107 which may turn in the vertical sides integral with the frame 103.

On the spindle 107 are fixed two chain wheels 108 and 109 each carrying an endless chain 110 and 111. On the left side both chains surround the two chain wheels 112 and 113 fixed on the spindle 114 rotatably mounted on the frame. The chain 111 is provided with two studs adapted to engage with the right extremity of lever 117 pivoting on a pivot 119 fixed on the bar 118 which may slide horizontally in guides fixed on the frame. The distance between the studs is equal to the half of length of the chain. When the motor turns the chain wheels clockwise, the stud 115 engages the lever 117, and thereby pushes the bar 118 to the left until lever 117 strikes against the roller 120 fixed on the frame. Roller 120 urges lever 117 out of engagement with the stud of the chain, whereby the movement of the bar is stopped. Just before, the stud 121 on the bar 118 will have rocked the lever 122 about the pivot 123, thereby interrupting the contact 124 in the motor circuit. The lever 122 is maintained in its new position by the pawl 125 pivoting on the stationary pivot 126.

The momentum of the motor moves the chain a little while after the circuit of the motor has been interrupted. This is of no importance, as the chain wheel may still turn more than half a revolution before the second stud of the chain reaches a position in which it could prevent the return of the bar 118. Said bar is provided with a bracket 127 which carries a picker 128 adapted to engage with the lower card of the pile 129, in such a way that when the bar 118 is moved to the left, a card will be pushed through the throat 130 until the front edge of the card reaches the claw 131 pivoting on a pivot 132 integral with the card carriage 133. Said carriage is further provided with a pusher 134 pivoted at 135 to the carriage, so that a card may raise the pusher and pass underneath. When the card has passed, the pusher rocks downwards because of its own weight, and prevents the card from moving back. The card is thus maintained fixed on the carriage in position for the verification of its first column. The carriage comprises further the rack 137 provided with rollers which may roll on the frame. To the right on said rack, a pivot 138 carries a pawl 139 adapted to engage with two studs 140, 141 fixed on the chain 110. The distance between the studs is equal to the half of the length of the chain. The stud 141 will engage with the pawl 139 and bring the carriage to the right. When the carriage has reached its extreme right hand position in which it will re-

ceive a new card pushed by the picker 128 which performs the opposite movement, the arm 142 of the pawl 139 strikes with its slant extremity against the roller 143 fixed on the frame, thus 5 disengaging the pawl from the stud of the chain, whereby the carriage is stopped. A spring 146 pulls constantly the carriage towards the left. The latter however is kept in position by the escapement pawl 145 which is engaged with 10 the rack 137. The verification is effected as previously described by the depression of the keys of a keyboard, whereby the corresponding contacts may directly be closed or opened as indicated on the wiring diagram Fig. 10. The escapement of the carriage may be operated mechanically by the depression of said keys, or by means 15 of a magnet 188 as shown in Fig. 10.

Finally, the keys 283a, 283b . . . 283l of the keyboard may control the contacts 284a, 20 284b . . . 284l which control the selecting magnets 170a, 170b . . . 170l as indicated also in Fig. 10. Each magnet 170a . . . 170l corresponds to a perforation in a column of the card. A magnet 170m controlled by the key 283m and the contact 284m is provided for column spacing. When a magnet is energised by the depression of a key 283a . . . 283m, its armature 180 Fig. 1, by means of a rod 181 rocks the corresponding lever 182 about the stationary pivot 183. Lever 182 rocks 25 30 in its turn the bail 184 about the stationary pivot 183. The pawl 185 pivoting on the pivot 186 fixed on the bail closes the contact 187 when the bail is rocked, thus establishing the circuit for the escapement magnet 188. The armature 189 of the latter rocks through the rod 190 the bell crank 191 about the fixed pivot 192. The two rods 193 and 194 are pivotally connected to the bell crank 191. The rod 193 is at its upper end pivotally connected on the lever 195 Figs. 1 40 and 23 which is fixed on the spindle 196 which may turn in the bearings 197 and 198 (Fig. 2) fixed on the frame. To the other end of the spindle 196 is fixed a lever 199 which carries an adjusting screw 200 adapted to push on the lever 201 (Fig. 1) pivoting on the pivot 203 fixed on the frame. Solid with lever 201 is a plate 570 which is adjacent to another plate 571 which may turn on a collar on the lever 201, concentric to the axis of the spindle 203, Fig. 22. A spring 572 fixed with its right end to plate 570 constantly urges plate 571 with its right edge 55 60 65 70 75 80 85 90 95 99 100 105 110 115 120 125 130 135 140 145 150 155 160 165 170 175 180 185 9550 9555 9560

its initial position, releasing lever 201. The spring 207 then swings the lever 201 clockwise whereby the pawl 145 engages with the rack, and disengages the pawl 202 from the rack. The latter is moved by the spring 146 Fig. 2 one tooth towards the left until it is blocked again by the pawl 145. The card is now in position for the verification of the second column.

The circuit for the escapement magnet 188 is interrupted by the downwards movement of the rod 194 which rocks the lever 211 pivotally connected to said rod 194. At its other end the lever 211 is pivotally connected at 186 to the bail 184. Lever 185 carries a projection 212 which by a spring is kept against the lower edge of lever 211. Lever 211 therefore rocks pawl 185 so that its right extremity disengages from the contact 187, whereby said contact is opened, and the circuit for the escapement magnet interrupted. The contact 187 may only be closed again after the bail 184 and thus the pawl 185 have been returned to their initial positions. However, if by the verification of a column the perforations do not correspond to the keys depressed on the keyboard, the bail will automatically be locked and prevented from returning to its initial position. The contact 187 cannot be closed again and the verifying operation is impossible before the machine is unlatched by the depression of the key "error" which automatically causes the imprint of a mark "error" on the card, and the ejection of said card in a separate receptacle.

After the verification of each column, the carriage advances one step to the left. When the last column has been verified, the carriage advances still a certain distance to the left. This additional movement engages the front edge of the card under a gripper 222 and initiates the following operations: removal of the gripper 131, closing of the contact 124 which controls the return of the carriage, the feeding of a new card, and the ejection of the verified card. During said additional movement, pawl 215 strikes with its lower extremity against the stop 216 (Fig. 2) fixed on the frame, releasing the gripper 131 which with its arm 217 was leaning against said pawl. The spring 218 then rocks the gripper 131 so that it is lowered below the track of the cards and the card is free to be ejected. Simultaneously the adjusting screw 219 (Fig. 2) fixed on the right extremity of the carriage rocks the pawl 125 Fig. 1, so that the latter releases lever 122 which, pulled by the spring 220 closes the contact 124 and thereby the motor circuit. On the bar 118 is fixed a roller 223 which is in contact with the upper edge of lever 224. This latter pivots on the pivot 225 fixed on the frame and its left extremity is provided with a toothed rack 226 constantly meshing with the toothed wheel 227. Said toothed wheel may rotate about the shaft 228 fixed on the frame and is integral with the wheel 229. The wheel 229 is constantly meshing with the wheel 230 loosely mounted on shaft 231 which may freely rotate in bearings integral with the frame. On shaft 231 is fixed a disc provided with three notches 233 and a drum 234 carrying three grippers 222 Figs. 1 and 24. The wheel 230 carries a pivot 235 on which pivots the lever 236. Said lever is provided with a nose adapted to engage with one of the notches of the disc 232 compelled by the spring 237. A pawl 238 prevents the disc from moving clockwise and insures correct position.

When the bar 118 is moved towards the left, the roller 223 rocks the lever 224 about the pivot 225. The toothed rack 226 then rotates wheel 227 which in its turn rotates wheel 230. Lever 236 turns with the wheel 230, engages one of the notches 233, turns the disc 232, and with it the shaft 231 and the drum 234.

When the drum has turned 120° the movement of the bar 118 is interrupted and the pawl 238 holds the drum in its new determined position. The grippers 222 are fixed on parts 239 which pivot on the pivots 540 fixed on the drum. Every part 239 is provided with a nose 541 which slides on a cam 542 fixed to the frame. A spring (shown Fig. 24) tries to rock the part 239 clockwise, so that the nose 541 presses against the cam 542. When the drum turns, the nose 541 is displaced on the cam 542. The end of the cam permits the part 239 to rock, pulled by said spring. The gripper 222 performs thereby a movement against the card which is engaged under the gripper and grips the card against the drum 234. By its rotation, the drum moves the card until the card, in striking with its front edge the stop 358 is withheld in the reception receptacle for the cards verified correct (357 Figs. 1 and 24). A spring 266 restores the lever 224 and thus the lever 236 to their initial positions while the drum is maintained in its new position by the pawl 238.

Verification

When the card is in position for verification, the column of the card to be verified is located under a contact roller 240 Figs. 5, 11 and 10. Said roller comprises a shaft 241 rotating freely in bearings fixed on the frame, and a series of conducting rings 242 insulated from each other by rings of insulated material 243. The rings 242 are insulated from the shaft 241 by a tube of insulated material 244. There is one conducting ring 242 above each place of perforation of a column of the card. For each conducting ring 242 there is a brush 245 fixed on an insulating plate 246 (Fig. 5) which is itself fixed on a bail 247. On each side the bail pivots on two pivots 248 fixed to the frame. A rod 254 connects the bail to the armature 255 of the magnet 256 so that when the magnet 256 is energized, the brushes 245 are leaning against the roller 240.

Above the roller 240 is placed a second row of brushes 260 fixed on an insulated plate 261. Each one of the brushes 260 makes contact with a conducting ring 242. When a card is in position of verification, a circuit may be established by a perforation from the lower brush 245 through the perforation and the ring 242 to the upper brush. To each brush is connected a conducting wire, according to the diagram Fig. 10.

Opposite the roller are placed two rows of contacts Fig. 5 comprising one unit 263 or 264 of contacts for each place of perforation in a column, that is for each key of the keyboard. Further there are units of contacts for the spacing, the tabulation, etc.

On every second lever 182 is fixed an arm 273. On each of the other levers is fixed an arm 274. On each arm 273 is fixed a stud 275 adapted to engage with the contacts of one of the units 264, when the corresponding lever 182 rocks, so that the corresponding contact 277 is closed and the two contacts 278 and 279 are opened. The arm 274 carries the stud 276 which operates in the

same way for the unit 263. A spring 280 fixed to the bail 184 tends to restore this latter in its initial position Fig. 5 when the corresponding magnet 170 is deenergized.

Circuit diagram

According to the invention, a column of the card has been verified "correct" if, during the verification of said column a magnet B has been energized, and a magnet A has remained non-energized. If the magnet B is not energized, or if the magnet A is energized, the machine will be locked. This locking is made by the bail 184 which is prevented from being restored to its initial position by one of the said magnets. In its locked position, the bail cannot close again the contact 187, and a further operation of the machine is impossible. Said conditions correspond to all possible combinations of errors as will be now explained.

Assume that there are two perforations 9 and 7 in the column to be verified and that the operator depresses the two corresponding keys 283a and 283c (Figure 10). The contacts 284a and 284c will be closed and the following circuits established: line 285, contacts 296 and 407, line 286, contacts 284a and c, magnets 170a and c, line 287, line 289. Said magnets close the contacts 277a and c and break the contacts 279a, 279c, 278a and 278c. Just afterwards the bail 184 will close the contact 187 and the following circuits are established: line 285, contact 296, contact 187, line 300, upper brush 260a, conducting ring 242a, perforation 9, brush 245a, contact 277a, line 309, contact 278b, brush 260c, ring 242c, perforation 7, brush 245c, contact 277c, line 307, contact 278d, contacts 278e, f, g, h, i, j, k, l, line 315, magnet B, line 289. The escapement magnet 188 will be energised by the circuit: line 285, contact 296, contact 187, line 316, magnet 188, line 289. If there are no other perforations, the magnet A will not be energised.

When the escapement magnet 188 is energised, it breaks the contact 187, which cannot be closed again and no circuit can take place before the bail 184 has been restored to its initial position. The magnet B has been energised, and the magnet A has not been energised, that is, no blocking of the machine has been effected as will be explained below. However the bail can only be restored to its initial position when the operator has removed his fingers from the keys, so that the contacts 284 are broken, and the magnets 170 deenergised. The actuation of the escapement magnet causes the displacement of the carriage as previously described, and the card is in position for the verification of a new column.

Assume now that in the example described, the column verified contained a third perforation, for instance the perforation 6, and that the operator has depressed only the two keys indicated, but not the key 6. The contacts 278d and 279d will still be closed, the circuit already described through the perforations 9 and 7 would not be changed, and the magnets B and 188 would be energised as described. But the magnet A would have been energised by a circuit which is the same as previously described through the perforations 9 and 7 until the contact 278c. From the contact 278c, said circuit divides through brush 260d, ring 242d, perforation 6, brush 245d, contact 279d, magnet A, line 289. The magnet A which is of a rapid working type will block bail 184, as will be explained later, so that said bail cannot be restored to its

initial position. Suppose in the above example that the perforation 9 did not exist in the column to be verified. The circuit through the perforations 9 and 7 cannot take place and the magnet B is not actuated which involves the locking of the bail 184. No change occurs in the working of the escapement mechanism and the card remains locked in the position of verification of a new column.

Suppose further that in the above example there is no perforation in the column and that the two keys 9 and 7 are depressed. The magnet B will not be energised and the machine will be locked. If there is no perforation in a column to be verified, and the operator depresses the space key 283m, the bail 184 will be rocked and the contact 187 closed. The other contacts remain in their initial positions as indicated Figure 10. The circuit through the escapement magnet will be established as previously described: The magnet B will be energised by the circuit: line 285, contact 296, contact 187, line 300, contacts 278a, b, c, k, l, magnet B, line 289. If the operator depresses the space key and another key simultaneously, and there is no perforation in the column to verify, one of the contacts 278 will be broken, magnet B will not be energised, and the machine will be locked. In case that all the cards in a stack of cards to be verified contain fields comprising a plurality of columns, which have no perforations, said fields can be automatically verified. To this effect, the carriage carries a bar 320, Figure 10, which has cut out portions 321 corresponding to the fields without perforations. On the bar slides the extremity 322 of a blade 323 of a stationary contact. When the hollow part of the bar arrives below the extremity 322, the contact 324 is closed, and a circuit for the space magnet established. Said circuit will be broken by the contact 189b every time the escapement magnet 188 is energised, so that the carriage moves automatically, until the verification of the field is finished and the contact 324 is broken by the bar. If there is a perforation in said field of the card, the magnet A will be energised as above described, and the machine will be locked. The bar which must have a determined and distinct shape for each different work, may be replaced by a double sliding contact 360, 361—Figure 10—fixed on the carriage 133 but electrically insulated from said carriage. The contact 360 slides on a common conductor 362, and the contact 361 on a bar 363 with a multitude of conducting spots. Each spot may be at will, connected to the line 364. This device may replace the parts 320 to 324 and be utilised for all different works.

The circuit for the space magnet is automatically established as follows: on the bail 184 is fixed a stud 390—Figure 10— which opens the contact 389 when the bail rocks. On the armature of the space escapement magnet 170m is fixed a stud 391 which opens the contact 388 when the space magnet is energised. The magnet 386 is energised by the following circuit: line 285, contact 296, line 410, contact 188b, contacts 389 and 388, magnet 386, line 411, line 289. Magnet 386 closes contact 385a which establishes the circuit for the magnet 387 which is maintained by its contact 387a. When the contact 324 is closed, the space magnet 170m will be energised by the circuit: line 410, contacts 188b, 387a, 324, space magnet, line 287. The contacts 389 and 388 will be interrupted, but the space magnet will be maintained by said circuit until

the escapement magnet 188 breaks the contact 188b. Simultaneously the contact 387a is broken. After the card has advanced a column, the two contacts 389 and 388 will be closed again, the magnets 386 and 387 will be energised, and if the contact 324 is still closed, the space magnet will be once more energised as above described. The space magnet opens a contact 170ma. The printing magnet 395 will therefore effect the imprint of a mark "verified" on the card, except when the space magnet is energised. 10

When the operator depresses the key 294, the contact 124 is closed establishing the circuit through the magnet 292. The contact 124 remains closed (Figures 1 and 10) and the contact 292a is opened breaking the circuit for the brush magnet 256. The contact 292b closes the circuit for the motor which will be maintained in operation until the bar 118 breaks the contact 124 as previously described. 20

Locking mechanism

The magnet B, Figures 7 and 8, is fixed on a plate 330 integral with the frame. The armature 331 is connected through a rod 332 to a lever 333 pivoted at 334. Lever 333 carries a pivot 335 on which pivots the lever 336. A spring 365 pulls the lever 333 against the stop 366. Another spring 337 holds the lever 336 in a determined position bearing with the extremity 338 against the lever 333. On a fixed axis 339 are pivoted three pawls 340, 341, 342. The pawl 340 is normally held in position by the spring 343 with its lower extremity bearing against the armature 344 of the magnet A. The pawl 342 is normally held in position by the spring 345 with its right upper edge against the stop 346. Its upper extremity is always in engagement with the nose 347 of lever 336. When the bail 184 rocks in clockwise direction Fig. 7, and when the magnet B is not energised, the pawl 342 moved by the spring 345 will engage under the arm 352 fixed with the bail as shown Fig. 7 and locks the bail in said position. 30

In the case where the magnet A has been energised, the armature 344 has released the pawl 340 so that said pawl moved by the spring 343 with its upper extremity will engage under the lever 352 and lock this latter and the bail 184. In the case where magnet B has been deenergised before the lever 352 has left its upper position, the nose 347 of lever 336 prevents the blocking of the bail 184 as shown Figure 9. 40

Unlocking mechanism

The pawl 341 carries an arm 348 on which is pivotally connected a rod 349 the lower extremity of which is connected to a lever 350 fixed on the shaft 351. The pawl 341 serves to assure that the key "error" can only be depressed when the bail 184 is in the locked position, that is the key "error" cannot be kept depressed during the verification. When said key "error" is depressed, the shaft 351 will turn a determined angle, causing the rocking of the pawl 341 towards the arm 352 fixed to the bail 184. Lever 355 fixed on the shaft 351 also rocks and swings with its curved extremity the pawls 340 and 342 in their positions indicated Figure 8, so that the arm 352 is released which permits the bail to return to its initial position. The lever 340 is at the same time locked by the armature 344. 50

The Figure 12 shows the key "error" 358 fixed on a rod 359 which may slide in two guides 560—561 integral with a plate 562 fixed on the frame. 75

On the rod 359 is fixed an adjustable part 563 sliding in a slot 564 of the plate 562. A spring 565 holds the key in its upper position. On shaft 351 is fixed an arm 566 drawn by a spring 367 against the fixed stop 368. When the operator depresses the key "error" the lower extremity of the rod 359 rocks the arm 566 and thus turns the shaft 351 which unlocks the machine as above described. 10

Printing

The part 563 Figures 11, 12 and 13 carries on a pivot 361 the pawl 370 held in position (Figure 11) by a spring 371 (Figure 13). A lever 372 pivots on the fixed pivot 373 and is held in position Figure 11 by the spring 374. On the lever 372 is fixed a stud 375 adapted to engage with the lever 376. This latter pivots on the fixed pivot 377, its arm provided with a printing projection adapted to effect a mark on the card. 20

When the key "error" is depressed, the pawl 370 engages with the nose 380 of lever 372 and rocks this lever counterclockwise. When said key is nearly completely depressed, the pawl 370 is disengaged from the nose 380 permitting the spring 374 to swing the lever 372 clockwise. The stud 375 will thereby strike against the lever 376 which with its projection 379 effects the printing. In one mode of execution, an inking ribbon is placed between the card and the projection 379. A mark "error" 488 is represented on the Figures 19 and 20. The spring 381 returns the lever 376 in the position of Figure 11 with an extremity bearing against the shaft 241. 30

The spring 381 is strong enough to counterbalance the spring 374 holding the lever 372 with its stud 375 against lever 376. When the key "error" moves upwards pressed by the spring 565 Figure 12, the pawl 370 may swing and pass the nose 380 and is restored to its position shown in Figure 11. After the printing of the mark "error" the machine is unlocked, and the verification may take place for the other columns of the card, or the operator may depress the key which releases the carriage for the immediate ejection of the card in a separate receptacle. Instead of printing a mark, the projection 379 may effect a special perforation. 40

During the verification, another mark, respectively 490 Fig. 19 and 489 Fig. 20 will be printed on the lower portion of the card to indicate that said card has been verified. This mark can be a line printed by an inking wheel, rolling on the card during its movement. Said wheel 55 may be mounted on the shaft 241 Figure 11 or to the left of said shaft. Said line could also be printed by repeated typing of a short line for each column. Means are provided to prevent the printing when the key for the releasing of the carriage will be depressed. 60

In one mode of execution, the imprint of the mark "verified" is effected by a lever 393 provided with a printing projection. 65

The mark "verified" is printed for each column before the verification for this column, has been completed and before the displacement of the carriage has taken place. 70

The imprint of the mark "verified" is thus effected, even if the column to be verified comprises an incorrect perforation. The mark "verified" therefore does not indicate that the column verified is correct, but only that said column has been verified. The mark "verified" in connection with the presence or the absence of a mark "error" for a determined column, will indicate 75

that said column has been verified correct or incorrect. Because the locking of the machine is effected only after the verified column has been displaced, the projection 379 for the imprint of the mark "error" is placed corresponding to the column which has just been verified, whereas the projection 394 for the imprint of the mark "verified" is placed corresponding to the column to be verified. The imprint of the mark "verified" is effected by the magnet 395 Figure 11. The armature 396 is by means of a rod 397 connected to lever 398 pivoted about a stationary pivot 399. A spring 400 keeps the lever in the position of rest, bearing against the stop 401. Lever 393 pivots on the stationary pivot 377 and is held in position of rest bearing against the axis 241 by the spring 405. When magnet 395 is energised, its armature rocks the lever 398 which with its nose 402 rocks the lever 393 so that the projection 394 prints a mark on the card. Magnet 395 Figure 10 is energised simultaneously with the magnet B by a shunt circuit through the contact 170ma. This contact which normally is closed, will be broken when the space magnet 170m is actuated as previously explained.

If the key 408 for the releasing of the carriage is depressed, the printing is not effected, the contact 407 Figure 10 being broken.

Said key 408 further rocks the lever 409 which moves the pawl 145 Figures 10 and 1 out of engagement with the rack of the carriage, permitting the advance of the carriage.

Ejection of incorrect cards

On the shaft 351 Figure 12 is fixed an arm 420 on which is pivotally connected a rod 421. Said rod is at its end pivotally connected on the lever 422 Figure 3 pivoting on the shaft 423 which may rock in a bearing 429 Figure 6 fixed on the frame. On the shaft 423 Figure 3 are fixed the levers 424 and 425. The latter is adapted to engage with the pawl 426 pivoting on the stationary stud 427. A spring 428 holds the pawl 426 against the nose of lever 425. When the key "error" is depressed and the shaft 351 turns a determined angle, the rod 421 turns the shaft 423 so that the lever 424 may take the position Fig. 4 locked by the pawl 426. When a card now is ejected, it strikes the extremity 430 (Fig. 6) of lever 424, rocks about the stud 431 fixed on the drum 234, thereby leaving the gripper 222, and is directed into a separate receptacle. Then a cam 435 fixed on the drum strikes against the arm 436 of pawl 426 Fig. 4, and rocks this latter so that the spring 367 Fig. 12 may return the lever 424 Fig. 3 to its initial position by means of the lever 566, the shaft 351, the arm 420 and the rod 421. The next card accordingly will be ejected into the ordinary receptacle.

Inking ribbon

The toothed wheel 440 Figure 11 is integral with the spindle 441 on which is fixed the spool 442 of the ribbon (Fig. 14). Another spool 443 is loosely mounted on the spindle 444. The ribbon 445 is conducted by a plate 446 above the printing position 447 of the card 448. The ribbon is moved by the wheel 440 which again is moved by the pawl 449 Fig. 11 pivoting on the stud 450 fixed on lever 451. This lever pivots on the spindle 441 and is held in position by the spring 455 Fig. 11 with its nose 453 near the projection 454 of lever 398. When the imprint of the mark "verified" has been effected by the magnet 395, the lever 398 moved by the spring

400 strikes with the projection 454 against the lever 451 which rocks, and by means of the pawl 449 advances the wheel 440 one tooth forward. The wheel 440 is held in position by the pawl 5 457.

Electric locking

Instead of locking the machine by locking the bail 184 as shown on Figures 7 and 8, the machine can be locked by the interruption of the supply circuit of the machine, whereby the mechanical devices shown Figures 7 and 8 may be omitted. The circuits necessary for such electric locking are indicated by the dotted lines Figure 10. The switch 460 is positioned to connect the battery to line 461. To start the operation of the machine, the key "error" indicated by T. E. Figure 10 must be depressed in order to close the contact 462. The magnet 463 is then energised by the circuit: line 461, contact 462, magnet 463, contact 464a, battery. The magnet 463 closes the contact 463a which maintains the magnet 463 energised as long as the contact 464a remains closed. The contact 464a remains closed as long as the magnet 464 is not energised. If, during the verification, the magnet B is energised as previously described, the contact Ba is opened every time the contact 188a is closed. The magnet 464 will therefore not be energised because the magnet B operates quicker than magnet 188, so that the contact Ba will be interrupted before 188a is closed. When the contact 187 is broken as previously described, no circuit can be established for magnet 464. On the contrary, if the magnet B is not energised, the contact Ba remains closed, and when the escapement magnet 188 is energised, and the contact 188a is closed, the magnet 464 will be energised by the circuit: line 461, contact 463a, contact 465, line 40 285, contacts 296, 401, 187, 188a, Ba, magnet 464, battery. The magnet 464 when energised opens the contact 464a which breaks the circuit for the magnet 463. The contact 463a consequently is opened, no circuit can be established, and the verifying operation is interrupted. The magnet 463 can only be energised again and the machine unlocked by the depression of the key "error" T. E., whereby the contact 462 is closed. When the key "error" is depressed, the contact 465 is opened, and no verification can be effected when the key "error" is depressed. The contact 462 will be closed only after the printing lever has been released and after the printing of the mark "error" is effected as described.

55 In the case where magnet A is energised, the contact Aa will be closed and establish the circuit for the magnet 464 and the machine will be locked as above described.

It is evidently possible to combine the two magnets 188 and B in one magnet. In this case, when a column is verified correct the magnet B effects the escapement, and when the column is verified incorrect, no escapement is effected and the machine remains locked.

65 *Alternative mode of execution of the wiring diagram*

Another mode of execution is shown in Figure 18. The contact roller 478 is composed of two conducting rings 479a, b, 480a, b for each analysing brush 475a, b. Each conducting ring is electrically insulated. There is an upper brush 476a, b, 477a, b, for each conducting ring, and two contacts 471a, b, 473a, b for each key 75 470a, b of the keyboard. When a key is de-

pressed, both contacts are opened. The brush 475a makes contact through a perforation coincidentally with the two conducting rings 479a, 480a. The bail 481 closes the contact 187 when a key is depressed. When a column is verified correct, the magnet B will be energised and the magnet A will not be energised. If there is a perforation 9 in a column and the corresponding key 470a, b has been depressed, the following circuit is established when the bail 481 closes the contact 187: Line 285, contacts 269, 187, line 423, brushes 475a, ring 480a, brushes 477a, line 484, contacts 471b, 471c, d, etc., 471l, magnet B, battery. Simultaneously the following circuit is established: line 285, contacts 269, 187; magnet 188, 15 battery. The magnet A is not energized. The conditions requested at the beginning of the present description are therefore realised, that is, the verification is effective for every possible combination of perforations and depression of 20 keys.

For instance, if there are two perforations 9 and 7 and the operator depresses only the key 470a, the magnet A will be energized by the circuit: Battery, contact 187, line 483, brushes 475a, 25 perforation, ring 480a, brushes 477a, line 484, contact 471b, brushes 475c, ring 479c, brushes 476c, contact 473c, line 425, magnet A, battery.

While I have described what I deem to be practical and efficient embodiments of my invention, it should be well understood that I do not wish to be limited thereto as there might be changes made in the arrangement, disposition and form of the parts without departing from the principle of my invention as comprehended within the scope of the appended claims.

What I claim is:

1. In a machine for verifying perforated cards, an escapement mechanism for moving a card in position for verifying the perforations of the columns, one column after another, a keyboard with a key for each perforation to be verified in a column of the card, a plurality of contacts operated by each key, a special contact which is common to said keys and which is operated as an incident to the operation of said first contacts, a circuit established by said special contact, said circuit passing in series each of the perforations in the column being verified which correspond to the keys depressed and one of said contacts operated by each key depressed, means for blocking the escapement of the machine if said circuit has not been established, and means for neutralizing said blocking means when said circuit has been established.

2. In a machine for verifying perforated cards, an escapement mechanism for moving a card in position for verifying the perforations of the columns, one column after another, a key for each perforation to be verified in a column of the card, a plurality of contacts operated from each key, a special contact which is common to said keys, said special contact being operated only when one or more of said plurality of contacts have been operated, a circuit passing in series said special contact, one of said contacts operated by each key depressed and the perforations which correspond to the keys which have been operated, a magnet operated by said circuit, means controlled by said magnet for blocking the machine if said magnet has not been operated during the verification of a column of the card, a second magnet operated by a circuit passing through the perforations which do not correspond to the keys which have been oper- 70

ated and means controlled by said second magnet for blocking the machine if said second magnet has been operated during the verification of a column.

5 3. In a machine for verifying perforated cards, an escapement mechanism for moving the cards into positions for verifying a plurality of perforations in a column of the card, one column after another, a row of contact members on each side 10 of the card for making contact through the perforations of a column of the card, each contact member in each row being normally insulated from the other, a keyboard with a key for each perforation to be verified in a column of the card, a plurality of contacts operated by each key, a circuit passing in series each contact member corresponding to a perforation for each key depressed and one of said plurality of contacts for each said key, a magnet operated by said circuit, and means whereby said magnet controls the operation of said escapement mechanism.

4. In a machine for verifying perforated cards, an escapement mechanism for moving the cards into positions for verifying the perforations in a column of the card, one column after the other, a key for each perforation in a column in position to be verified, a plurality of contacts operated by each key, a circuit passing in series each of said perforations and one or more of the contacts operated by each key, a magnet actuated by said circuit, and means whereby said magnet controls the operation of said escapement mechanism.

35 5. In a machine for verifying perforated cards, an escapement mechanism for moving the cards into positions for verifying a plurality of perforations in a column of the card, one column after another, a keyboard, a key for each perforation to be verified in a column of the card, one 40 or more contacts operated by each of said keys, said contacts preparing circuits through the perforations of the cards, one of said circuits passing a magnet A and any perforation in the column being verified which does not correspond to any key depressed, another of said circuits passing a magnet B and in series each of the perforations in the column being verified which corresponds to the keys depressed and one of said contacts operated by each key depressed, a 45 special contact for establishing one or more of said circuits when said first contacts have been operated, means for operating the escapement mechanism when said magnet B has been operated and said magnet A has not been operated, and means for rendering the escapement mechanism inoperative when said magnet B has not been operated or said magnet A has been operated.

60 6. In a machine for verifying perforated cards, an escapement mechanism for moving the cards step by step into position for verifying the perforations in each column of the card, a keyboard, a key for each perforation to be verified in said column, one or more contacts operated by each key, a bar common to said keys and adapted to oscillate in one direction when one of said keys is depressed, an escapement mechanism, means for operating the escapement mechanism when one of said keys is depressed, means whereby the escapement operation can only be completed when said bar has oscillated in the other direction returning to its initial position, a circuit prepared by said contacts, which circuit when established passes the perforation or perforations corresponding to the key or keys depressed, an-

other circuit which, when established passes a perforation which does not correspond to any key depressed, two magnets each operated by a different one of said circuits and means whereby said bar will be blocked when a determined one of said magnets is operated or the other is not operated during the verification of said column.

7. In a machine for verifying record cards, an escapement mechanism for moving the cards step by step into positions for verifying the indications in each column of the card, a keyboard, a key for each indication to be verified in a column of the card, means for verifying the indications in a column when the corresponding keys are depressed, means for automatically marking each column that is verified, means comprising a contact operated by the card carriage when a column of an empty field of the card is in position to be verified for the automatic verification of the columns of said empty field, and means for the automatic suppression of said marking when one of said columns of said empty field is verified.

8. In a machine for verifying perforated cards, an escapement mechanism for moving the cards step by step into positions for verifying the perforations of each column of the card, a keyboard, a key for each perforation to be verified in said column, one or more contacts operated from each key, a special contact which is common to said keys and which is operated as an incident to the operation of said first contacts, a first circuit established by said special contact, which circuit passes in series the perforations of the column to be verified and further, for each key depressed, passes a contact operated by said key, an escapement magnet controlling the escapement mechanism, said escapement magnet being operated by a circuit established by said special contact, and means for rendering said escapement mechanism inoperative when said first circuit is not established coincidently with the operating of said escapement magnet.

9. In a machine for verifying perforated cards, an escapement mechanism for moving the cards step by step into positions for verifying the perforations in each column of the card, a key for each perforation to be verified in said column, one or more contacts operated from each key, a special contact which is common to said keys and which is operated as an incident to the operation of said first contacts, a circuit prepared by said first contacts which circuit when established by said special contact passes the perforation or perforations corresponding to the key

or keys depressed, means for operating said escapement mechanism when a key is depressed, and means for rendering the escapement mechanism inoperative when said circuit has not been established, said inoperativeness being effective only when the card has been moved a further step and a new column is in place for verification.

10. In a machine for verifying perforated cards, an escapement mechanism for moving the cards step by step into positions for verifying the perforations in each column of the card, a key for each perforation to be verified in said column, one or more contacts operated from each key, a special contact which is common to said keys and which is operated as an incident to the operation of said first contacts, a circuit prepared by said first contacts which circuit when established by said special contact passes the perforation or perforations corresponding to the key or keys depressed, means for operating said escapement mechanism when a key is depressed, means for rendering the escapement mechanism inoperative when said circuit has not been established, said inoperativeness being effective only when the card has been moved a further step and a new column is in place for verification, and means for the automatic marking of every column verified, also when this column is verified incorrect.

11. In a machine for verifying perforated cards, an escapement mechanism for moving the cards step by step into positions for verifying the perforations in each column of the card, a key for each perforation to be verified in said column, one or more contacts operated from each key, a special contact which is common to said keys and which is operated as an incident to the operation of said first contacts, a circuit prepared by said first contacts which circuit when established by said special contact passes the perforation or perforations corresponding to the key or keys depressed, means for operating said escapement mechanism when a key is depressed, means for rendering the escapement mechanism inoperative when said circuit has not been established, a special error key, means for marking in a determined column of the card a special mark "error" when said key is depressed, and means whereby an escapement render inoperative can be rendered operative when said error key is depressed.

KNUT A. KNUTSEN.
